UNITED STATES PATENT OFFICE.

JOSEPH M. VAIL, OF BRYAN, OHIO.

RAIL-STAY.

1,074,666.

Specification of Letters Patent.

Patented Oct. 7, 1913.

Application filed May 3, 1913. Serial No. 765,337.

To all whom it may concern:

Be it known that I, JOSEPH M. VAIL, a citizen of the United States, and a resident of Bryan, in the county of Williams and State of Ohio, have invented a certain new and useful Rail-Stay; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to devices adapted for use in conjunction with railway rails and the supporting ties thereof to prevent a relative creeping of the rails and ties, but is not restricted to such use as it may be used 20 in any connection for which it may be adapted or appropriate.

The object of my invention is the provision of improved means of this character, which is simple and inexpensive of manufacture, and capable of being easily and quickly applied to a rail without the use of bolts or other retaining means.

A further object of my invention is to provide a single-piece device of this nature, 30 which is automatically operable to firmly clamp a rail upon a creeping movement of the rail in one direction relative to an associated supporting tie, whereby the rail and tie are caused to move together.

35 The invention is fully described in the following specification, and while, in its broader aspect, it is capable of embodiment in numerous forms, a preferred embodiment thereof is illustrated in the accompanying drawings, in which,—

Figure 1 is a plan view of portions of a rail and supporting tie therefor equipped with my invention. Fig. 2 is an enlarged perspective view of the device, and Fig. 3 is 45 a bottom plan view thereof.

Referring to the drawings, 1 designates a railway tie, and 2 a rail supported thereby, to the base of which a device comprising my invention is clamped. This device comprises a bar or body member 3, which is intended to extend beneath a rail from one side to the other thereof, preferably in flat contact with its base, and is provided at one end with a clamping head or jaw 4 for engaging around one side edge of the rail base.

The head 4 is disposed transversely of the bar 3 and has one end preferably projected beyond the bar, as shown. A spring-bar 5 extends from the projected end of the head 4 in the general direction of projection of the body member 3 from such head, and is of sufficient length to adapt it to extend from one side to the other of a rail base beneath the same, and has its free end terminating in a jaw or head 6 for clamping a rail base in opposition to the head 4, as shown in Fig. 1. The bar 5 is preferably, but not necessarily, integrally connected at its inner end to the head 4, and is provided intermediate its ends with one or more loops 7, or is otherwise suitably formed, to adapt its free end to yieldingly grip a rail base in opposition to the head 4 and to have lengthening movements relative to such head to facilitate a springing of one or the other of the clamping heads into or out of engagement with a rail base when the other clamping head is engaged with the opposite edge of the base.

The clamping head 6 projects toward the free end portion of the body bar 3, and has its outer side longitudinally tapered or beveled, as shown at 8, to adapt it to work within the angled or laterally projecting end portion 9 of the body bar 3 and to co-operate therewith to effect a relative compressing or rail base binding action of the clamping heads 4 and 6 when the free end portions of the bars 3 and 5 are moved toward each other, which movement is permitted by reason of the yielding connection 90 theretwixen.

The body bar 3 is preferably provided on its under side with reinforcing webs 10, and on its outer side or that opposed to the bar 5, with a tie abutment 11. This abutment 95 is preferably disposed adjacent to the inner end of the bar to lessen the liability of breaking the bar from the head 4 when a tie moving stress is communicated by the device from a rail to a tie.

In the use of this device it is engaged with the base of a rail at the near side of a tie in the direction of creeping action of a rail, in position for the abutment 11 of the body bar 3 to have contact with the tie side, 105 whereby a creeping movement of the rail will cause the engaged end of a tie to have corresponding movement therewith, as is well understood in the art. In applying one of my devices to a rail, it is placed under the 110

base thereof with the head 4 in engagement with one side edge of the base, and the clamping-head 6 is then sprung outward to adapt it to be engaged around the opposite edge of the rail base. The contractile action of the spring connection between the clamping heads 4 and 6 is sufficient to normally retain such heads in yielding clamping engagement with the rail base and at the same time is adapted to permit a yielding movement of the body-bar 3 longitudinally of the rail and relative to the spring-bar 5. In placing a device in engagement with a rail, the abutment 11 should be placed in contact with the side of a tie toward which the rail may have a tendency to creep, as shown in Fig. 1, the creeping tendency in such figure being in the direction indicated by the arrow. Upon a creeping action of the rail the abutment 11 of the body-bar 3 has its thrust against the tie so that the tie opposes a creeping movement of such bar, thus causing the free end portion of the bar to spring toward the bar 5 and the angled end portion 9 thereof to coact with the wedge surface 8 of the clamping-head 6 to effect an opposed tightening action of the clamping heads 4 and 6 against the rail base, whereby the device is rigidly held to the rail so that any further creeping action of the rail will be positively communicated to the tie.

For the purpose of durability and cheapness of construction it is preferable to cast my anti-rail creeping device in a single piece from malleable iron, as such metal is sufficiently yieldable in its nature to permit of a relative yielding action of the clamping heads and also of the bars 3 and 5. It will be understood, however, that my invention is not limited to the use of any particular material or to the construction of the device in a single integral piece, as the same function might be performed by securing several parts together as is apparent.

It is evident that my device may be easily and quickly engaged with a rail base without the use of bolts or any other securing means, and that the clamping heads thereof are connected for yielding movements transversely of a rail while the body-bar 3 and the part connecting the two heads are adapted to have relative yielding movements longitudinally of the rail.

I wish it understood that my invention is not limited to any specific construction, form or arrangement of the parts except in so far as such limitations are specified in the claims.

Having thus described my invention, what I claim as new, and desire to secure by Letters Patent, is,

1. A device of the class described having opposed spring connected rail-base clamping parts, and a part yieldingly movable

relative to said clamping parts for coöperating with the connection therebetween to tighten such parts against a rail-base.

2. A device of the class described comprising a pair of connected relatively movable cross members one being longitudinally yieldable and having rail-base clamping parts at opposite ends thereof, said members having parts coöperating to impart a clamping action to the clamping parts when the members have relative predetermined movements.

3. A device of the class described having a plurality of yieldingly connected cross-bars, and rail-base clamping members carried by the bars for relative yielding movements transversely of a rail, one of said bars serving as a thrust member.

4. A device of the class described having a pair of opposed rail-base clamping parts, and a looped member yieldingly connecting said parts beneath an engaged rail-base and normally maintaining the same in clamped engagement therewith, one of said parts having a tie abutting portion separate from said looped member.

5. A device of the class described having two bars for projecting under a rail base, said bars being yieldingly connected and having a rail clamping member adjacent to their connected ends and one bar being yieldable transversely of a rail and having a rail clamping member at its free end, while the other of said bars serves as a thrust member and is operable when pressure is exerted thereon in one direction to coöperate with the free end portion of the longitudinally yieldable bar to effect a rigid clamping of said members against an interposed rail-base.

6. A device of the class described having a pair of cross-bars yieldingly connected for relative transverse movements and one being longitudinally yieldable and having opposed rail-base clamping parts at opposite ends thereof, the other bars serving as a thrust member and operable when moved transversely in one direction relative to the longitudinally yieldable bar to effect a rigid clamping of the rail clamping parts against an interposed rail.

7. A device of the class described having a pair of opposed rail-base clamping parts, a longitudinally yieldable connection between said parts, and a thrust member projecting from one of said parts and being yieldable relative to said connection transversely thereof and having a portion for coacting with said parts to effect a rigid clamping of a rail thereby when said member is moved in one direction relative to said connection.

8. A single-piece device of the class described having a thrust part, a pair of opposed rail-base clamping parts, and a longi-

tudinally yieldable connection between said clamping parts for normally maintaining the same in clamping engagement with an interposed rail-base.

- 5 9. A single-piece device of the class described having yieldingly connected cross-bars one being longitudinally yieldable and having opposed rail-base clamping parts at opposed end portions thereof, said bars being adapted to coact at their free end portions when relatively contracted to effect a relative contraction of the clamping parts.
- 10 10. A single-piece device of the class described having a pair of cross-bars which are connected for relative transverse yielding movements, one of said bars serving as

a thrust member and the other being longitudinally yieldable and having opposed rail-base clamping parts adjacent to its end portions, the free end of said longitudinally yieldable bar having wedge coaction with the free end portion of the thrust bar when said bars are relatively contracted whereby to effect a relative contraction of the clamping parts.

25

In testimony whereof, I have hereunto signed my name to this specification in the presence of two subscribing witnesses.
